PRINTING PRESS

Oscar C. Roesen, Scarsdale, N. Y., assignor to
 Wood Newspaper Machinery Corporation,
 Plainfield, N. J., a corporation of Virginia

Application April 12, 1941, Serial No. 388,312

13 Claims. (Cl. 101—349)

This invention relates to improvements in a printing press and is particularly applicable when employed in connection with a high speed press such as used by most metropolitan newspapers.

The principal objects of the invention are to provide a press which operates at high speed with means contained within itself for preventing the fine mist of ink which, by the action of centrifugal force, is apt to be distributed by such a press, from being thrown outside the press where it can do any damage; to provide a removable disposable absorbent or other ink retaining medium on the inside of the guards or other adjacent surfaces upon which a film of ink readily deposits from the mist thrown off by the rollers.

Broadly the present invention relates to certain improvements pertaining to enclosures for the inking mechanism of printing presses. Safety codes require printing presses to be provided with guards and enclosures at such points where rotating rollers, cylinders and other moving parts about the printing unit would be liable to damage from entrance of foreign matter or where such exposed mechanism would be likely to cause physical injury. Obviously, guards or enclosures for this purpose are necessarily in close proximity to inking rollers which run at high speeds and throw off, due to the centrifugal action, fine particles of ink in the form of a mist which settles and gradually accumulates on any convenient surface but more noticeably on the guards enclosing the said inking rollers and creating as it does a troublesome problem in keeping the press reasonably clean and free from accumulation of such ink.

The primary object of the present invention is to provide a disposable absorbent or ink retaining medium on the inside surface of such enclosing guards or other adjacent surfaces upon which a film of ink readily deposits and is retained thereon, by absorption or otherwise from the mist thrown off by high speed inking rollers.

A further object of this invention is to provide means for easily removing this ink retaining medium and replacing it with a fresh surface on which subsequent ink mist will collect.

With these and other obvious objectives and advantages not specifically referred to, this invention consists in such novel arrangement as shown in the accompanying drawings but it should be understood that variation in constructional details may be resorted to without departing from the scope of the invention.

Reference is to be had to the accompanying

drawings wherein corresponding numerals of reference indicate corresponding parts in the several views.

In the drawings Figure 1 is a diagrammatic end view of a printing unit provided with mechanism, shown in section, for receiving the ink absorbing material;

Figure 2 is a view in side elevation of Figure 1;

Figure 3 is an enlarged detail of the mechanism shown in Figure 1 for winding the ink retaining material from one roller to the other;

Figure 4 is a fragmentary view of another form of holding mechanism for the ink retaining material;

Figure 5 is a view in side elevation of Figure 4;

Figure 6 is a fragmentary side view of the upper portion of the holding mechanism shown in Figure 4;

Figure 7 is an enlarged detail of the holding mechanism shown in Figure 4;

Figure 8 is an enlarged detail of the same part shown in Figure 7 but in the holding position;

Figure 9 is a modified form of means for mounting the ink retaining material on the guards;

Figure 10 is a sectional view on the line 10—10 of Figure 9;

Figure 11 is a top plan view of the form shown in Figure 9.

In the drawings 1 indicates the ink mechanism guard or shield provided at the upper and lower edge thereof with extensions or projections 2 which serve as bearings into which the winding reel shaft 3 and unwinding reel shaft 4 are journaled.

The guards 1, as usual, are enclosed and surround the printing rolls and the ink retaining material 5 is unwound from the lower roll shaft 4 on to the upper roll shaft 3 on the inside of the guards 1. This ink retaining material 5 it is to be understood remains in a fixed position on the inside of the guards until it has become charged or coated with the ink mist and is then unwound from the lower roll shaft on to the upper reel shaft.

The reel shafts 3 and 4 are so constructed at one end to receive a handle or wrench for turning same and in the form shown in Figures 1 and 3 is fitted with a ratchet disc 6 and pawl 7 whereby the rolls or reels are securely locked and held against rotation and the ink retaining material 5 held taut when in use.

The ink retaining material may be of any desired character provided, of course, that it is such as will retain the ink mist and prevent the

spreading of same outside of the guard. A roll of any absorbent paper would be very satisfactory but blotting paper or paper such as is used in the manufacture of paper towels or newsprint could well be used. Newsprint paper is readily available in a printing plant and it would be an exceedingly simple matter to provide rolls of newsprint paper for this purpose. This newsprint paper as is well known is quite absorbent. It is, of course, possible that cloth such as burlap might be utilized as the absorbent. The invention, however, is broadly to the use of any ink retaining material for this purpose and it is not intended to be restricted to any particular material provided, of course, that it will retain the ink either as a coating or by absorption. Any readily destructible, decomposable material may be utilized for the purpose.

In the use of this invention, shown particularly in Figure 1, after the ink retaining material has become coated or saturated or has absorbed the ink mist the sheet is wound up on to the upper reel from the lower reel and an entirely new surface presented for further use. After the entire lower roll has been utilized or unwound the used ink retaining material on the upper reel is removed and a fresh roll placed on the lower reel and connected with the upper reel for future use.

In the form shown in Figure 4 the upper reel is dispensed with and the sheet of absorbent or ink retaining material 5 is passed over the top of the guard 1 and held taut by means of a clamp bar 8 which is fulcrumed in the bearings 2 at the upper part of the guard. There is provided a spring 9 secured at one end, 10, on a pin projecting from the side of the guard 1 and at its other end to a pin 11 on the clamp bar 8. This spring exerts a pressure on the clamp bar so that the member 12 thereof contacts the sheet after it is passed under the bar and locks the same in taut condition.

The clamp bar is also provided with an extension 13 which may be swung to the left and hold the clamp bar open when in the position shown in Figure 8 permitting the saturated or soiled ink retaining material to be pulled out and cut off. When the soiled material has been cut off from the sheet and disposed of the fresh portion is in position for receiving the mist. The guard or bar in this form is then thrown down to the position shown in Figure 7. A handle or lever 14 is formed on the clamp bar for convenience in swinging the same from locked to open position and vice versa.

In the form shown in Figures 9 and 10 the ink retaining material in sheet form is inserted in between guides 16 secured to the inside of the guard 1 and when these sheets 15 become saturated or coated with ink mist they may be readily slipped out of the guides and replaced with fresh clean sheets for further use.

Having thus fully described my invention what I claim as new and desire to secure by Letters Patent of the United States is:

1. In a printing machine including ink distributing mechanism, means for collecting the ink mist created by the rapidly rotating ink distributing mechanism within the proximity of the ink distributing mechanism, said means comprising a sheet of absorbent material capable of absorbing and retaining a substantial amount of the ink mist located outside of the ink distributing rolls and enclosing the ink distributing mechanism.

5 2. In a printing machine including ink distributing mechanism, means for collecting the ink mist created by the rapidly rotating ink distributing mechanism within the proximity of the ink distributing mechanism, said means including a guard enclosing the ink distributing mechanism, and a sheet of absorbent material mounted on the side of said guard adjacent the ink distributing mechanism.

15 3. In a printing machine including ink distributing mechanism, a guard adjacent the ink distributing mechanism for preventing the dispersal of the ink mist created by the rapidly rotating ink distributing mechanism outside of said guard and a sheet of absorbent material mounted on the inner side of said guard for receiving and absorbing said ink mist.

20 4. In a printing machine including ink distributing mechanism, a guard adjacent the ink distributing mechanism for preventing the dispersal of the ink mist created by the rapidly rotating ink distributing mechanism outside of said guard, a roll rotatively mounted at the top and bottom edges of said guard, a roll of absorbent material on one roll and means for unwinding the sheet of absorbent material from one roll on to the opposite roll.

25 5. In a printing machine including ink distributing mechanism, a guard adjacent the ink distributing mechanism for preventing the dispersal of the ink mist created by the rapidly rotating ink distributing mechanism outside of said guard, a roll rotatively mounted at the top and bottom edges of said guard, a roll of absorbent material on one roll, and means for locking and holding taut on the guard a sheet of said absorbing material unwound from one roll on to the other.

30 6. In a printing machine including ink distributing mechanism, a guard adjacent the ink distributing mechanism and a sheet of absorbent material mounted on the inner side of the guard for receiving and absorbing the ink mist created by the rapidly rotating ink distributing mechanism.

35 7. In a printing machine including ink distributing mechanism, means formed of absorbent material adjacent the ink distributing mechanism and capable of absorbing and retaining a substantial amount of the ink mist created by the rapidly rotating distributing mechanism and preventing the dispersal of said ink mist outside of said means.

40 8. In a printing machine including ink distributing mechanism, a guard adjacent the ink distributing mechanism for preventing the dispersal of the ink mist created by the rapidly rotating ink distributing mechanism outside of said guard, a roll rotatively mounted at one edge of said guard, a roll of absorbent sheet material on said roll, and means for locking and holding taut on the guard the absorbing material unwound from said roll and drawn over the other edge of the guard.

45 9. In a printing machine including ink distributing mechanism, a guard adjacent the ink distributing mechanism for preventing the dispersal of the ink mist created by the rapidly rotating ink distributing mechanism outside of said guard, guides formed on the inner face of said guard and a sheet of absorbent material held in said guides for receiving and absorbing said ink mist.

50 10. In a printing machine including ink distributing mechanism, a guard in the proximity

of the ink distributing mechanism, a disposable liner on the side of the guard adjacent the ink motion for collecting ink mist.

11. In a printing machine including ink distributing mechanism, means formed of ink retaining material adjacent the ink distributing mechanism capable of receiving and retaining a substantial amount of the ink mist created by the rapidly rotating distributing mechanism and preventing the dispersal of said ink mist outside of the means.

12. In a printing machine including ink distributing mechanism, means arranged in proximity to the ink distributing mechanism formed of readily decomposable material capable of col-

lecting and retaining a substantial amount of the ink mist created by the rapidly rotating distributing mechanism and preventing the dispersal of said ink mist outside of the means.

13. In a printing machine including ink distributing mechanism, a sheet of readily disposable absorbent material arranged in proximity to the ink distributing mechanism and forming a guard adjacent the ink motion for collecting and retaining a substantial amount of the ink mist created by the ink distributing mechanism and preventing the dispersal of said ink mist outside of the guard.

OSCAR C. ROESEN.
